UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed January 18, 1924. Serial No. 686,944.

To all whom it may concern:

Be it known that I, JOHN F. O'CONNOR, a citizen of the United States, residing at Chicago, in the county of Cook and State of Illinois, have invented a certain new and useful Improvement in Antifriction Bearings, of which the following is a full, clear, concise, and exact description, reference being had to the accompanying drawings, forming a part of this specification.

This invention relates to improvements in antifriction bearings.

One object of the invention is to provide a simple, practical and relatively inexpensive roller bearing, especially adapted for use as a railway car side bearing and wherein the parts are so arranged that the anti-friction element proper is automatically returned to its normal central position under the influence of gravity, when free from load.

Another object of the invention is to provide a device of the character indicated that is self-contained, all the parts of which are maintained in permanently assembled relation and which is adapted to be applied as a unit to a bolster of a railway car.

Other objects and advantages of the invention will more clearly appear from the description and claims hereinafter following.

In the drawing forming a part of this specification, Figure 1 is a vertical sectional view taken through the ends of the body and truck bolsters of a railway car, showing my improvements in connection therewith. And Figure 2 is a vertical sectional view corresponding substantially to the line 2-2 of Figure 1.

In said drawing, 10 denotes the underside of the body bolster and 11 the upper side of the corresponding opposed truck bolster. The improved side bearing is shown as applied to the truck bolster and comprises, broadly, a base casting, retaining member or housing A; an anti-friction element proper B; and counterweights C-C at the ends of said anti-friction element.

The housing A is of more or less box-like form having curved end walls 13-13, and vertical side walls 14-14, each of the side walls having a laterally offset section 15 for a purpose hereinafter described. A plate 12 is arranged in the bottom of the housing, and a hardened wear plate 16 is arranged on the

plate 12, and is held in place in a recess 17 in the bottom of the housing, the plate 12 being secured to lugs 116 of the housing. The side walls of the housing are provided with openings 19 at the lower ends to facilitate the removal of dirt, cinders or other foreign matter from the housing. Rivets 20 may be used for securing the plate 12 to the truck bolster.

The anti-friction element B is in the form of a cylinder adapted to roll back and forth in either side of central normal position on the bearing plate 16. This roller is provided with an axial opening 21 therethrough to receive a pin 22. Openings 23 are provided through the side walls of the housing in alinement with one another, so as to permit of the pin being assembled with the roller while the latter is in the housing. The pin is entered through one of the openings 23 before the plate 16 is applied, so that when the plate is in position, the pin will be elevated above the opening 23, and the parts will then be maintained in their assembled relation.

The counterbalanced means are of like construction and are arranged at the opposite ends of the anti-friction element proper. The counterbalanced means are made up of a plurality of parts and in the present instance, each comprise a pair of disks or rollers 26, rotatably mounted at the lower corners of a triangular hanger or supporting member 25, the latter being in turn pivotally mounted at its upper corner to the projecting portion of the pin 22. The roller or disks 26 are adapted to move in the offset portions 15 of the housing, the latter forming guideways therefor. The guideways are so shaped and proportioned that they have opposed parallel, vertical, side walls, and the disks 26 of each pair being so spaced slightly, and when arranged on the hanger 25, they engage the opposed parallel vertical walls of the guideway when the anti-friction element proper is in its normal central position, thus preventing to a large extent any tendency of the anti-friction element to shift to either side of its normal position when free from load. When in normal position, the disks of each pair are at the same elevation, and arranged on opposite sides of the vertical axis of the anti-friction element. The top flanges 27 of the guideways act as stops to

prevent the anti-friction element from being lifted out of the housing.

The operation of the device is as follows, assuming the movement of the anti-friction element proper is to the left as viewed in Figure 1. As the element B rolls to the left on its bearing surface 16, it oscillates the hangers 25 carried thereby about their pivotal centers 22, lifting one of the rollers or disks 26 of each pair above the other, out of engagement with their cooperating guiding walls of the housing, and at the same time causes the other disks of the pairs of disks to roll downwardly of their cooperating vertical guide walls, to the position shown in dotted lines in Figure 1. It is apparent that the counterbalanced means will be in a position of unstable equilibrium in the position shown in dotted lines so that when the load 10 is released, the right-hand disks under the influence of gravity, will oscillate the hangers about their pivotal centers, returning the anti-friction element proper to its normal central position, and causing the left-hand disks to roll upwardly of their cooperating guiding walls, all the disks being at the same elevation when in normal position. It should be noted that the anti-friction discs themselves contribute the major portion of 20 the counterbalancing weight, so that when they are unbalanced by reason of the movement of the roller and contact with the guides, they are largely responsible for returning the anti-friction element to normal position, as well as reducing friction between the counterbalanced means and the guides.

It will be noted that in the arrangement shown, wherein the hangers are oscillated to lift one of each pair of disks above the other, there is always a direct pull on the anti-friction roller to return it to normal position, even when the roller is near its central position, thus producing a maximum torque and returning effect on the roller causing it to return rapidly to normal position. By employing the disks as shown, it is evident that the friction during the return movement is greatly minimized, thus promoting the sensitiveness of the return action.

I have herein shown and described what I now consider the preferred manner of carrying out my invention but the same is merely illustrative and I contemplate all changes and modifications that come within the scope of the claims appended hereto.

I claim:

1. In an anti-friction bearing, the combination with a bearing surface; of an anti-friction element proper, arranged to move on said bearing surface to either side of normal position; means connected to said element, said means including a plurality of independent anti-friction means disposed to operate as counterbalancing weights; and

means cooperating with said anti-friction means for unbalancing the same during movement of said element.

2. In an anti-friction bearing, the combination with a housing; of an anti-friction element proper within said housing, and arranged to move from side to side thereof; of substantially triangular supporting members movable with said element, and having anti-friction rollers arranged in positions to provide counterbalancing weights; said housing cooperating with said anti-friction rollers to unbalance the same during movement of said element.

3. In an anti-friction bearing, the combination with a bearing surface; of an anti-friction element proper adapted to move on said bearing surface to either side of normal position; of means pivotally connected to said anti-friction element, and having a plurality of anti-friction means offset with respect to said connection; and means for guiding said anti-friction means in a path at an angle to the movement of said element.

4. In an anti-friction bearing, the combination with a housing; of an anti-friction element arranged to move from side to side of said housing; means connected with said element including a plurality of anti-friction means arranged to operate as counterbalancing weights; said housing being arranged for guiding said anti-friction means during movement of said element, and to prevent the removal of said anti-friction means therefrom.

5. In an anti-friction bearing, the combination with a bearing surface; of an anti-friction element proper adapted to move on said bearing surface to either side of normal position; of guide means extending at an angle to the movement of said element; and counterbalanced members connected to said anti-friction element and having enlarged lower portions, including anti-friction means arranged to bear against said guide means to unbalance said members during movement of said anti-friction element.

6. In an anti-friction bearing, the combination with a housing adapted to be mounted on a bolster; of an anti-friction element proper disposed within said housing; pendant carrier frames pivoted at each side on the axis of said element; and a pair of disks pivotally carried by each frame and being normally at the same elevation, said housing being provided with vertical guideways to normally engage both disks of each pair of disks, whereby when said element is shifted from its normal position, one of the disks of each pair, dependent upon the direction in which the element is shifted, is elevated above the other to a position of unstable equilibrium, the other disk rolling

vertically downwardly on said guideway, whereby when the load is released, said disks will return to their normal position under the influence of gravity.

7. In an anti-friction bearing, the combination with a housing having vertical guideways at its sides; an anti-friction element disposed within said housing arranged to roll back and forth therein; carriers pivotally hung from the axis of said element at either end; a pair of roller disks rotatably carried at the lower ends of each of said carriers and engaging the opposed vertical side walls of the guideways, whereby when said element is shifted to one side of its normal central position, each carrier will be tilted about its pivotal connection with the element, to disengage one of the discs of the pair of disks from its cooperating side wall and elevate it above the other, while the last-mentioned disk rolls vertically downwardly on its cooperating vertical wall.

8. In an anti-friction bearing, the combination with a housing having vertical

guideways at both sides; an anti-friction element disposed within said housing to roll back and forth therein; a pin projecting axially from the opposite ends of said element; carriers pivotally hung on said pins, and a pair of disks rotatably carried at the lower ends of each of said carriers on opposite sides of the vertical axis of said element, one of the disks of each pair engaging one of the opposed vertical side walls of the guideways, whereby when said element is shifted to one side of its normal central position, each carrier will be tiltably lifted to disengage one of the disks carried thereby from its cooperating vertical side wall and elevate it above the other, while the last-mentioned disk maintains its rolling contact with its cooperating vertical wall.

In witness that I claim the foregoing I have hereunto subscribed my name this 14th day of January, 1924.

JOHN F. O'CONNOR.
